COMBUSTION APPARATUS

Alan Sharpe, Ellwood, Melbourne, Australia, assignor to Power Jets (Research and Development) Limited, London, England, a British company

Application July 18, 1951, Serial No. 237,375

Claims priority, application Great Britain July 27, 1950

6 Claims. (Cl. 60—39.71)

This invention relates to combustion apparatus in which combustion of liquid fuel is required to be supported by a stream of air or other gas (hereinafter referred to as "air") flowing through a duct with a flame-extinguishing velocity and its primary object, stated in general terms, is the provision of such an apparatus which will offer the possibility of effective and efficient combustion over a wide range of operating conditions. The invention has particular application to the supporting of continuous combustion by means of such a fast moving air current involving a large mass flow, as for example, in gas turbine or other jet propulsion power units and in gas turbines for other purposes.

The expression "flame-extinguishing velocity" is used here to indicate that the mean speed of the stream in its general direction of flow through the duct, calculated from the ratio of the air volume passing in unit time to the cross-sectional area of flow path, is substantially higher than the speed of flame propagation in the fuel-air mixture concerned. For hydrocarbon fuels burning in air the speed of flame propagation is considered as being of the order of one foot per second at atmosphere temperature; the invention, on the other hand, is especially applicable to combustion apparatus for so-called "ram-jet" propulsion power units, as well as to other jet propulsion units and to gas turbine power units in general, in which the general velocity of the air stream calculated on the basis indicated, might be of an order as low as 10 or as high as 500 feet per second or even more, depending on the design.

Satisfactory operation of a combustion system of the kind indicated over a wide range of air mass flow and density requires that the flame should not be extinguished under any conditions of operation and in order to prevent this the range of air-fuel ratios over which burning will take place must be as wide as possible whilst maintaining combustion efficiency at a reasonable level with weak mixture. Further it is desirable that pressure losses should be low and that an even temperature distribution over the cross section of the flow should be achievable. Apart from the necessity for providing some means of preventing the flame from being blown out by the air flow, these requirements involve amongst other things the attainment of a high standard of mixing as between the combustion air and the fuel to be burnt, and of atomization and distribution in the case of a liquid fuel. A common practice in gas turbine and similar combustion systems is to inject liquid fuel droplets into an almost stagnant region which is protected by a baffle from the full blast effect of the air flow, specially designed atomizing injection nozzles, or impact surfaces arranged in the path of the fuel jet, being provided to achieve satisfactory atomization of the fuel; fuel once ignited in this stable zone will continue to burn and ignite further incoming fuel.

According to the present invention, there is provided a combustion apparatus in which combustion has to be supported by a ducted air flow of flame-extinguishing velocity and in which means are provided for forming in the flow a stabilized flame wherein fuel droplets and a

part of the airstream constituting primary air are led into the combustion chamber through a mixing duct, the flow of the air-fuel mixture so formed is reversed in direction and led through a vaporizer around said mixing duct, and the flow of the mixture is then again reversed in direction and led to a primary combustion zone in the combustion chamber to form a flame around said vaporizer; further air from the main airstream may mix at high velocity with the burning gases at a region downstream of the primary combustion zone.

In this way the heat of the burning gases serves to vaporize the fuel, most of this vaporization taking place within the vaporizing duct, while at the same time the axial length of the apparatus is minimized.

In a preferred form of the invention, the mixing duct is co-axial with and occupies a central region of the main duct carrying the main airstream and is in the form of a diffuser whereby the velocity of the primary air is reduced as it moves downstream through said mixing duct, fuel being injected (preferably downstream) into said mixing duct at the region of its upstream end, i. e. at a region of high velocity. At the downstream end of this duct the flow of unburnt fuel and primary air is reversed in direction to pass upstream through the vaporizing duct and may be accelerated on its path through this duct by the provision of swirl vanes therewithin.

At the upstream end of the vaporizing duct the flow of the fuel-air mixture is again reversed in direction and led into a primary combustion zone in the combustion chamber around the vaporizing duct, and at this region the velocity of the fuel-air mixture is greatly reduced to assist flame stabilization.

The burning gases then flow downstream from the combustion zone towards the outlet to the main duct and are preferably accelerated so that they finally emerge into the main duct at high velocity. Downstream of this outlet the remainder of the main airstream mixes at high velocity with the burning gases to complete combustion and/or to cool the gases.

A detailed view of the combustion apparatus according to the invention, in axial section, is shown in Fig. 1 of the accompanying drawing while external views of a cylindrical combustion apparatus and an annular combustion apparatus respectively are shown in Figs. 2 and 3.

In this drawing the main duct may be a cylindrical tube 1 as in Fig. 2 or an annular duct 21 as shown in Fig. 3. The device according to the invention is a pilot burner located in the duct upstream of the main fuel supply. The pilot fuel supply connection is shown at 22, the main fuel supply connection at 23 and the terminals of an ignition sparking-plug at 24 in all figures. The inlet for the air (or other combustion-supporting gas) stream is at the left-hand end of each figure and the outlet for combustion product gases at the right-hand end.

Figs. 2 and 3 are each partly broken away to show the interior; Fig. 1 is an enlarged sectional view showing how this revealed part looks in both cases.

The main airstream carried in the main duct 1 is divided into two parts by a tubular combustion chamber 11 mounted concentrically therein, part of the air flowing through an annulus 2 between duct 1 and the combustion chamber while another part of the air flows through the pilot burner device incorporated in the combustion chamber 11. The main combustion zone is defined by the main duct 1 downstream of the main fuel injector 15, the upstream limit of this zone being indicated at 25. Concentrically mounted within the combustion chamber 11 is a tubular mixing duct 3 which is a diffuser progressively increasing in diameter from the inlet at an upstream position in the main duct 1 to the outlet further downstream. The combustion chamber is open at the downstream end; the mixing duct 3 is shown as con-

stituted by a concentric divergent re-entrant portion of the combustion chamber 11, joined to the outer wall of chamber 11 by the smoothly curved end wall 9 at the upstream position. The duct 3 is open at both ends. Also concentrically mounted within the combustion chamber 11 and enveloping the mixing tube 3 is the tubular vaporizing duct 7 closed at the downstream end by the smoothly curved end wall parts 5. The duct 7 is mounted on the outside of the wall of the mixing duct 3 by vanes 8.

For introducing fuel droplets into that part of the air-stream which passes through the pilot burner, a fuel injector 4 is located within the main duct at the upstream end of the inlet to the mixing duct 3. For convenience the injector 4 can be of the ordinary swirl atomizer type, because the conical jet of swirling droplets which issues from this type gives a good distribution of the droplets across the cross-section; this good distribution is important although with this invention a high degree of atomization is not necessary.

When the airstream of high velocity enters the left-hand end of the main duct 1, fuel is injected into this stream at a region of high velocity by the injector 4 having the previously-mentioned fuel connection 22. As the mixture of unburnt fuel drops and air flows downstream through the interior of the diffuser duct 3, the fuel and air become well mixed together and at the downstream end of duct 3 the flow of the fuel-air mixture is reversed in direction by means of curved walls 5 which lead the mixture into the annular vaporizer passage 6 formed between the vaporizing duct 7 and the mixing duct 3. Within the annulus 6 the vanes 8 are swirl vanes whereby the fuel-air mixture is rotated around the axis of the system on its path upstream.

At the upstream end of the annular passage 6 the flow of the fuel-air mixture is again reversed by means of the curved walls 9 which define a primary combustion zone 10 in which the velocity of flow is reduced so that a stabilized flame can be formed, as explained below. From here the burning gases can travel downstream again through the space 12 in the combustion chamber outside the vaporizing duct 7. Thus it will be seen that the burner device constituted by parts 3, 7 and 11, defines a flow path which, as shown by arrows in the drawing, passes along the interior of the duct 3, then reverses direction to pass along the interior 6 of the vaporizing duct 7; finally the path reverses again into and along the the space 12 in the combustion chamber 11, and so re-emerges in the main duct, where combustion products from the combustion chamber will meet the part of the airstream which flows over the outside of the burner device through the space 2. Furthermore, it will be seen that the cross-sectional area of the path, after increasing along the mixing duct 3, decreases on entering the space 6 and then increases considerably again on entering the space 10 in the combustion chamber; in the example shown in the drawing the cross-sectional area of the space 6 at all sections is less than that at the outlet from duct 3 while the cross-sectional area of the flow path at the beginning of space 10 is greater than that at the outlet from duct 3. Thus in one typical case, when the general air velocity in duct 1, and hence the velocity at the inlet to duct 3, is 550 ft. per second, the velocity decreases to 100 ft. per second at the outlet from the duct 3, increases from 200 ft. per second to 260 ft. per second during passage through the space 6, and decreases still more to 28 ft. per second on entry into the primary combustion zone 10.

Now although a velocity of 28 ft. per second in a steady stream would be too high to maintain stable combustion it is found that in the space 10, with a reduction to this speed and a complete reversal of direction, conditions are formed which allow stable combustion to be maintained there or more particularly at the entrance to the space 12. Once the mixture has been ignited here in any way, combustion will be maintained in the space

12; the flame will heat the vaporizing duct 7, to ensure substantially complete vaporization of the liquid fuel which will continue to be ignited as it emerges from the space 6 into the stable zone of combustion. For convenience in initially starting the combustion an ignition sparking-plug 14 may be provided where shown, and having terminals 24 as already mentioned. The variation in cross-section of the space 12 is such as to increase the velocity of the burning gases as they move downstream towards the outlet 13 of the combustion chamber 11 where the burning gases mix with the remainder of the airstream flowing at high speed through the space 2 and combustion is completed in the downstream portion of the main duct 1.

For compactness, the vaporizing duct 7 is of substantially the same length as the mixing duct 3 so that the outlet from the vaporizing duct into space 10 is in the same region as and disposed around the inlet to the mixing duct 3; the combustion chamber 11 is also of about the same length, the outlet end of the mixing duct 3 and the closed end of the vaporizing duct 7 being both adjacent to the outlet end 13 of the combustion chamber.

The flame issuing from the outlet 13 serves as a pilot flame for main fuel injected into the main duct 1, for example from a series of fuel nozzles provided symmetrically around the outlet 13 by the annular fuel tube 15 having the previously-mentioned fuel-supply connection 23 and shown with three sets of nozzle apertures 15^a, 15^b and 15^c directing fuel jets perpendicularly across the duct, upstream and downstream respectively; only such of these sets as are desired need be provided.

The combustion apparatus set forth may be used for various purposes. It may be the essential part of a ram-jet device, it may be connected between the compressor and the turbine of a gas-turbine plant or in a jet-propulsion gas-turbine plant it may be connected to the end of the exhaust pipe of a gas-turbine as a jet pipe, with re-heating by after burning.

What I claim is:

1. A combustion device for burning liquid fuel droplets carried in a gas stream, comprising a combustion chamber, a vaporising duct within and extending along said combustion chamber and having an outlet into said chamber, and a mixing duct within and extending along said vaporising duct having at one end an inlet open to receive the liquid carrying gas stream and at the other end an outlet into said vaporising duct, said chamber and ducts together defining a flow path for the gas stream which passes along the interior of said mixing duct to the outlet thereof, reverses direction to pass along said vaporising duct outside the mixing duct to said outlet of the vaporising duct, and then reverses again into and along said combustion chamber outside said vaporising duct, and ignition means in said combustion chamber for initiating combustion therein and accordingly, by heat transfer to the gas stream flowing through said vaporising duct, vaporising the fuel carried therein, wherein said combustion chamber and ducts are so dimensioned that the part of said flow path defined within said vaporising duct outside said mixing duct has in any transverse section plane a flow area less than either the transverse flow area of said mixing duct at the outlet thereof or the flow area of said combustion chamber in a transverse plane at said outlet of the vaporising duct.

2. A combustion device for burning liquid fuel droplets carried in a gas stream, comprising a combustion chamber, a vaporising duct within and extending along said combustion chamber and having an outlet into said chamber, and a mixing duct within and extending along said vaporising duct having at one end an inlet open to receive the liquid carrying gas stream and at the other end an outlet into said vaporising duct, said chamber and duct together defining a flow path for the gas stream which passes along the interior of said mixing duct to the outlet thereof, reverses direction on to pass along said vaporising duct out-

side the mixing duct to said outlet of the vaporising duct, and then reverses again into and along said combustion chamber outside said vaporising duct, and ignition means in said combustion chamber for initiating combustion therein and accordingly, by heat transfer to the gas stream flowing through said vaporising duct, vaporising the fuel carried therein, wherein said combustion chamber and ducts are so dimensioned that the part of said flow path defined within said vaporising duct outside said mixing duct has in any transverse section plane a flow area less than either the transverse flow area of said mixing duct at the outlet thereof or the flow area of said combustion chamber in a transverse plane at said outlet of the vaporising duct, and said part of said flow path has swirl vanes provided therein.

3. A combustion apparatus wherein liquid fuel is to be burnt in a high-velocity stream of combustion-supporting gas comprising, in combination, of a main duct for the gas stream, a burner device connected to receive part of said stream from one region of the main duct and to discharge said part into the rest of the flow in a region of said main duct lower down stream, and an injector located in said main duct for injecting fuel droplets into said part of the stream, wherein the burner device is made up of a combustion chamber with an outlet end discharging into the main duct at said last mentioned region, a vaporizing duct within and extending along the combustion chamber, and a mixing duct within and extending along the vaporizing duct with an inlet end open to receive gas from the main duct at said first mentioned region, the whole burner device defining a flow path which passes along the interior of the mixing duct, reverses direction to pass along the vaporizing duct, outside the mixing duct, and then reverses again into and along the combustion chamber outside the vaporising duct and thence back into the main duct, said burner device including an igniter in said combustion chamber for initiating combustion therein and accordingly by heat transfer to the gas stream flowing through said vaporizing duct, vaporizing the fuel carried therein.

4. A combustion apparatus according to claim 3 in which said burner device is a pilot burner and there is a main injector located to inject fuel droplets into the main duct in the path of the gas rejoined by gas from the said pilot burner.

5. A combustion apparatus according to claim 3 having the said burner device located within and extending along the main duct, the inlet end of the mixing duct directed

upstream and the outlet end of the combustion chamber directed downstream, with clearance space around the outside of the burner for the passage of that part of the gas stream which does not go through the burner.

5 6. A combustion apparatus in which combustion of liquid fuel is to be supported by a high-velocity gas stream, comprising, in combination, of a main duct for the gas stream, a cylindrical burner device lying centrally along the said main duct to afford one path for part of the gas 10 through the burner device and another path for the rest of the gas over the outside of the burner device, and a fuel-droplet injector within the main duct in the region of the upstream end of the burner device, the burner device being made up of a tubular combustion chamber open at the downstream end, a tubular mixing duct, open at the downstream and upstream ends, constituted by a concentric, divergent, re-entrant tubular portion of the combustion chamber, and a vaporizing tube, closed at the end thereof downstream with respect to the direction of flow of the 15 gas stream in said main duct but open at the upstream end, concentrically within the combustion chamber enveloping the mixing duct but with said closed downstream end spaced from the mixing duct, the interior of the burner device thus defining a flow path from the main duct downstream through the mixing duct with progressively increasing cross-section, then upstream, with decreased cross-sectional area, through the vaporizing duct, reversing again, with increase of cross-section to an area greater than the cross-sectional area at the outlet from the mixing 20 duct, into the combustion chamber and therealong until re-emerging into the main duct, the burner device including an igniter in said combustion chamber for initiating combustion therein and accordingly, by heat transfer to the gas stream flowing through the vaporizing duct, vaporizing the fuel carried therein.
